[57] CLAIM

The ornamental design for a biological sample cup or the like, substantially as shown and described.

DESCRIPTION

FIG. 1 is a perspective view from the top front of the biological sample cup, or the like, showing my new design;

FIG. 2 is a top plan view thereof;

FIG. 3 is a front elevational view thereof;

FIG. 4 is a bottom plan view thereof; and

FIG. 5 is a longitudinal cross section view thereof.
